SLIDE FOR SLIDE FASTENERS

John B. Mucci, Medford, Americo F. Sico, Somerville, and Tancredi Iapicca, Boston, Mass.

Application July 1, 1938, Serial No. 217,010

1 Claim. (Cl. 24—205)

This invention relates to slides for slide fasteners or zippers.

The primary objection to the conventional slide of a slide fastener or zipper resides in the fact that the same cannot be removed from its track intermediate the ends thereof unless the slide is pried loose therefrom and rendered unfit for any further use. The necessity for removing a slide intermediate the ends of its track arises frequently and may be due to many causes, for instance, it happens frequently that a garment gets caught between the slide and zipper track of another garment and the slide cannot be moved on the track so as to release the caught garment without tearing the same, or sand gets in the zipper track of a bathing suit or other beach wear and defies all attempts of moving the slide so as to open the track. Any such occurrence is not only annoying and sometimes embarrassing, but the replacement of a slide requires expert skill which involves cost and causes inconvenience.

It is the primary aim and object of the present invention to provide a slide which can be removed at any place on the zipper track without requiring any sliding movement thereon and without impairing the further use of the slide.

This object is accomplished by providing separate plates for the slide and hingedly connecting the same, and by providing means for interlocking the plates in cooperative position.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings:

Fig. 1 is a fragmentary plan view of a slide fastener unit which embodies the present invention.

Fig. 2 is a section taken substantially on the line 2—2 of Fig. 1.

Figs. 3 and 4 are fragmentary sections similar to Fig. 2, showing certain parts of the slide in different positions of operation, however.

Fig. 5 is a perspective view of the assembled slide, showing the parts thereof in position for removal from the track of the slide fastener.

Fig. 6 is a perspective view of one of the separate plates of the slide.

Fig. 7 is a plan view of a modified slide assembly.

Fig. 8 is a section taken on the line 8—8 of Fig. 7.

Referring to the drawings and more particularly to Fig. 1 thereof, the reference numeral 10 designates any suitable article such as a garment, to which the teeth or claws 11 of a track 12 of a slide fastener or "zipper" are secured in a conventional manner. The slide 13 for opening and closing the track 12 comprises two plates 14 and 15 on opposite sides of the track 12, said plates being rigid and having 15 the customary side flanges 16 (see particularly Figs. 2 and 5) which force the claws 11 of the track into the interlocked relation shown in Figs. 1 and 2.

Plate 14 is provided with the conventional track-opening post 18 which is wedge-shaped at 19 as best shown in Figs. 5 and 6. This post 18 is provided with a hole 20 which serves as a bearing for a pivot 21, provided by the plate 15. This pivot 21 is a rib formed by slotting the plate 15 as at 22 near and parallel to the rear edge 23 of said plate whereby said rib is also laterally exposed toward the remainder of the plate 15 to such an extent that said plate may pivot about the axis of the hole 20 into various angular positions as, for instance, the position shown in Fig. 4, without interference from the post 18. The post 18 is split at 24 adjacent the hole 20 so that the pivot or rib 21 of the plate 15 can be inserted into said hole through the slit 24. After insertion of the pivot 21 into the hole 20, the slit 24 is closed under pressure or in any other convenient manner so that the plate 15 remains permanently pivoted on the other plate 14. In order to avoid any interference between the track 12 and the plate 15, the hole 20 is so spaced from the track that the end portions of said plate on both sides of the pivot 21 thereof clear the track in any angular position of the plate 15. To this end, a length of 45 the plate 15, including the rib or pivot 21, is bent out of the plane of the remaining plate length as shown at 25 (Figs. 2 and 4). It is to be understood that the explained pivot connection between the plates 14, 15 is a preferred one, 50 and that any other pivot connection may be used without departing from the scope of the present invention.

The post 18 is also preferably provided with a stop 26 on which the plate 15 rests when both 55

plates 14, 15 assume the cooperative position shown in Fig. 2. A circumferential portion 18a of the post 18 near the pivot 21 is preferably formed slightly eccentric with respect to the pivot axis so that the edge 27 of the notch 22 becomes wedged thereagainst when the plate 15 is turned into the cooperative or closed position shown in Fig. 2 during the latter part of such rotation. The wedging engagement between the edge 27 of the notch 22 and the eccentric surface 18a of the post 18 acts as a lock for the closed plates 14, 15 (Fig. 2) against any relative movement between said plates other than relative rotation therebetween. The stop 26 on the post 18 may even be dispensed with if the eccentric surface 18a is so arranged that the edge 27 of the notch 22 becomes "firmly" locked thereagainst when the plate 15 is in the cooperative position shown in Fig. 2. Of course, the wedging surface 18a need not be eccentric but may be a mere inclined surface.

The post 18 is also provided with a notch 30 (see particularly Figs. 1, 5 and 6) in which a latch end 31a of a wire spring 31 is yieldingly retained for interlocking the plates 14 and 15 against relative rotation when they are in the cooperative position shown in Fig. 2. The spring 31 may be mounted in any suitable manner on the plate 15, but is preferably anchored on a punched-out and downwardly bent finger 32 of a casing 33 which is suitably mounted on top of the plate 15, for instance, by depending lugs 34 on opposite side walls of said casing 33 as well as the free end of the finger 32 which project into corresponding apertures in the plate 15 and are spot welded or otherwise secured therein. More particularly, the spring 31 is provided with two looped portions 35 and 36 of which portion 35 surrounds the finger 32 and thus anchors the spring 31 to the plate 15. It appears best from Fig. 1 that the non-coiled latch end 31a of the spring 31 leads from the coiled portion 35, while another non-coiled end portion 31b of said spring, hereafter called the "lock end," leads from the looped portion 36 and has its free end bent and extending at 37 through the plate 15 and between two consecutive claws 11 of the track 12, thus serving as a lock against movement of the slide along the track. The latch end 31a of the spring 31 is worked into a convenient, yet non-obstructing, handle 38 to facilitate manipulation of said latch end out of the notch 30. It will also be observed in Figs. 1 and 2 that manipulation of the latch end 31a of the spring 31 out of the notch 30 tends to further wind the coiled spring portion 35 so that the full spring force of the latter is used for retaining said latch end in the notch 30. Likewise, withdrawal of the lock end 31b of the spring 31 from locking engagement with the track 12 tends to further wind the coiled spring portion 36 so that the full spring force of the latter is used for locking the slide on the track. In view of the above tendencies of the manipulated spring ends 31a and 31b on the respective coiled spring portions 35 and 36 and due to the fact that these spring ends are manipulated in transverse planes, it follows that said coiled spring portions 35 and 36 are located in transverse planes as best shown in Figs. 1 to 4, inclusive.

The casing 33 is provided in two of its opposite side walls with notches 40 which serve as fulcrums for two lateral lugs 41 of a handle 42 which extends into said casing 33 through a slot 43 therein. As best shown in Figs. 2 and 4, inclusive,

the lugs 41 are of greater length than width in cross-section and one of these lugs (Fig. 1) extends underneath the lock end 31b of the spring 31. Hence, in the position of the handle 42 as shown in Fig. 2, the lock end 31b of the spring 31 is effective and locks the slide 13 against movement on the track 12, while rotation of the handle 42 into the position shown in Fig. 3, for instance, causes withdrawal of said lock end 31b from locking engagement with the track 12. Accordingly, if it is desired to manipulate the slide 13 along the track, the handle 42 has to be turned clockwise from the position shown in Fig. 2, preferably into the position shown in Fig. 3, before the slide is released for movement on the track 12. Rotation of the handle 42 into the position shown in Fig. 3 prior to manipulation of the slide 13 on the track 12 does not impose a burden upon the user of the zipper because the same will have to turn the handle away from the non-obstructing position shown in Fig. 2 in order to obtain a good grip thereon for working the slide. On the other hand, the handle 42 is best located in the least obstructive position shown in Fig. 2 when the slide is not worked, so that the instinctive manipulation of said handle into the position shown in Fig. 2 after working the slide automatically locks the same against further movement on the track.

If the slide 13 has to be removed from the track 12 for any reason whatsoever, the user of the zipper merely manipulates the latch end 31a of the spring 31 out of the notch 30 and turns plate 15 into an open position, such as shown in Fig. 4, whereupon the slide can be removed from the track without necessitating any sliding motion thereon. After the obstruction in the track is removed therefrom, the user of the zipper re-applies the slide to the track in the manner shown in Fig. 4 and then merely turns plate 15 into the position shown in Fig. 2 in which the latch end 31a of the spring 31 will snap into the notch 30 under its own spring force and thus re-lock the two plates 14 and 15 against relative rotation. While the plates 14, 15 are rotated relative to each other, the latch end 31a of the spring 31 rides on the edge 18b of the post 18. Thus, removal of the slide 13 from the track 12 and its re-assembly therewith does not require any special skill and may be quickly and efficiently undertaken by the user himself.

Figs. 7 and 8 disclose a modification of the slide in which the hinged connection between the plates 14a and 15a is afforded by means of a U-shaped leaf spring 50, the legs 51 and 52 of which are secured in any suitable manner to the respective plates 14a and 15a, and the yoke 53 of which is free to move independently of either plate 14a or 15a and preferably projects into a groove 54 in the wedge-shaped track-opening post 55 of the plate 14a. More particularly, the post 55 is provided with an extension 56 which projects between upturned ears or lugs 57 of the plate 15a to which the leg 52 of the spring 50 is secured in any suitable manner, such as by brazing or welding, not shown. The extension 56 of the post 55 is provided with a hole 58 into which normally projects one end of a plunger 59, slidably supported by upturned punched-out lugs 60 of the plate 15a and normally urged into registry with said hole 58 by a compression spring 61. The other end of the plunger 59 is preferably provided with a convenient handle 62 to facilitate withdrawal of said plunger from registry with the hole 58. Thus, the plunger 59

interlocks the plates 14a and 15a against relative opening rotation from the cooperative position shown in Fig. 8 in which the plate 15a rests on a stop or shoulder 63, conveniently provided by the post 55 of the plate 14a. Withdrawal of the 5 plunger 59 from registry with the hole 58 will permit the operator of the zipper to rock plate 15a away from the track (not shown) substantially to the dotted line position shown in Fig. 8, whereby the yoke 53 of the spring 50 is bent in the manner shown in dotted lines in said figure 10 and acts as a hinge. To further facilitate removal of the slide from the track, the post extension 56 is preferably provided with another 15 hole 65 with which the spring-urged plunger 59 will register when the plate 15a is sufficiently turned.

We claim:

A slide for a fastener track having two spaced 20 track-closing plates of substantially non-resilient

material of which one plate has an opening, a yoke of resilient material joining the plates at one end and permitting relative rocking movement of said plates in a plane at right angles to the main plane of either plate and parallel to the longitudinal axis thereof, a track-opening post on the other plate projecting between said plates and having a stop surface engageable by said one plate to prevent rocking movement of the latter toward said other plate beyond substantial parallelism therewith, said post having a portion extending through said opening in said one plate with slight clearance therefrom, and means cooperating with said extended portion of the post for locking said one plate against rocking movement out of engagement with said stop surface. 15
